TUBE SOCKET

Alvero C. Gregson, Garden City, and Martin Rennie, Hicksville, N.Y., assignors to the United States of America as represented by the Secretary of the Army

Application February 28, 1958, Serial No. 718,389

1 Claim. (Cl. 339—93)

This invention relates to improvements in electron tube sockets and more particularly to a floating mounting therefor to render it self-aligning.

It is well known that in electronic apparatus designed to operate at frequencies of the order of one-hundred megacycles or more, the connections between components in the circuits should be as short as possible. This is particularly true of components connected to the amplifying tubes. One means by which these short connections to the tubes may be effected is by eliminating the tube socket, which is standard with most low power tubes, and connecting the chassis ground directly to the pins at a point near where they are sealed to the tube. There is no difficulty in making these connections to low power tubes where the currents are comparatively small. However, for high power amplifier tubes, such as for instance the present day transmitting tubes type 4X150-A or 4X250, it is necessary that the connecting devices be flexible in order that strains set up by the heating action of the large currents will not crack the glass seal of the tube. Another important consideration in these transmitting tubes is that the pin contacts to which the cathode is connected be short to provide the required low cathode lead inductance for high frequency operation.

With the foregoing in mind, it is an object of this invention to provide an improved self-aligning and floating tube socket.

A further object of this invention is to provide a socket with short low inductance leads and having mechanical flexibility.

Accordingly, it is a feature of the present invention to adapt a conventional tube holder with supporting means permitting the connection of at least some of the pins of a tube to a circuit with short sliding contacts, and still allow the pins to be free for movement in response to heating.

For a more detailed description of the invention, together with other and further objects thereof, reference is had to the following description taken in connection with the accompanying drawing, wherein:

Fig. 1 is an enlarged bottom plan view of the socket;

Fig. 2 is a cross-section along line 2—2 in Fig. 1; and

Fig. 3 is a perspective view of a metallic ring, on a reduced scale, forming part of the invention.

In Fig. 2 the invention is illustrated in its adaptation to a conventional molded tube holder 10 constructed of insulating material, and preferably provided with a plurality of holes in the top; as may be seen in Fig. 2 one of such holes 12 is shown in the broken away portion of the drawing. These holes will, of course, be of the proper size and arrangement to accommodate the pins of the tube or other device for which the holder is designed. A conventional transmitting tube, the base 14 of which is shown in dotted lines, is inserted in the holder 10. For clarity, one pin 16 of the tube base 14 is shown in contact with its metallic sleeve 18, one of a plurality of sleeves which extend through the holder 10 to termini-

2

nate in conventional conducting lugs 20, 22, 24 and 26, to which the necessary connections may be attached for connecting the tube into a circuit. While only the ends of four lugs are shown in Fig. 1, the holder may have additional lugs for the connection of other circuit wires.

A metallic saddle 28 is attached to the holder 10 by a flexible retaining ring 30, said saddle being provided with holes 32 and 34 for mounting the holder to metal plate support 36 with fasteners such as rivets 38 and 40. Circular metallic spacers 42 and 44 are arranged concentrically within saddle mounting holes 32 and 34 respectively. The external diameter of the spacers is smaller than the diameter of said holes to permit circumferential and radial movement of the saddle with respect to the spacers. In addition, these spacers prevent any clamping of the saddle that might occur upon fastening at this particular spot to the metal plate 36.

Mounted in contact with saddle 28 is a metallic ring 46, best seen in Fig. 3, having opposite flat surfaces. The flat surface of ring 46, next to saddle 28, is provided with two oppositely disposed longitudinal channels 48 and 50. These channels provide a recess for the end portions of saddle 28 and permit the ends of the saddle to be mounted therein. Since the channels are deeper than the thickness of the end portions of saddle 28, the latter can move axially in said channels. The end portions are also narrower than the channels so that the saddle can also move laterally in said channels. An apertured metallic disc 52 is securely held in contact with the bottom surface of ring 46. As shown in Fig. 2, the aperture 53 of disc 52 is larger than the bottom diameter of holder 10, and the conducting lugs 20, 22, 24 and 26 projecting from the latter, extend through said aperture. Disc 52 is a cathode terminal disc to which lugs 20 to 26, which are all cathode lugs, are to be connected. For this purpose, flat strips 54, 56, 58 and 60, constructed of resilient sheet metal cut and shaped in the desired manner, are provided with slots at one end wherein the lugs 20, 22, 24 and 26 fit respectively. In assembly, the lugs are inserted into the slotted ends of their respective strips and soldered, while the other ends of the strips make a sliding contact with disc 52. Associated with the strips 54, 56, 58 and 60 are spring fingers 62, 64, 66 and 68 which are provided to form with disc 52 a number of pressure gripping bearings for the strips. Each of the metallic spring fingers 62, 64, 66 and 68 is formed with a bend at a point intermediate its ends, so that they slidably engage the strips 54, 56, 58 and 60 at points further inward from the free ends of same, and add a desired degree of yielding support to the tube holder 10. If necessary, excess portions of lugs 20 to 26, which may extend beyond the point where they are soldered to their respective strips should be cut off to permit a maximum amount of lateral movement of the holder 10, and thus prevent contact with the extreme turned down ends of spring fingers 62, 64, 66 and 68 when the holder shifts.

The arrangement of the spring fingers is such that the strips frictionally engage their respective spring fingers to form a good electrical connection therebetween. The other ends of the spring fingers are held securely between two similar metallic ring spacers 70 and 72 which are employed and disposed as shown in Fig. 2, one on each side of the fingers.

The rivets 38 and 40 secure together ring spacers 72 and 70, spring fingers 66 and 62 respectively, disc 52, ring 46, saddle 28 and spacers 42 and 44, respectively, and fasten these members to the metal support 36. Two other rivets 74 and 76 secure together ring spacers 72 and 70, spring fingers 68 and 64, respectively, disc 52 and ring 46.

The construction as described and shown affords a floating mounting and permits the holder 10 to move lat-

erally and axially with respect to the metal plate support 36 and the rivets 38 and 40, and compensate for structural or manufacturing variations in the tube pin locations and also for the differences in the coefficient of expansion of the metal plate 36 and the glass seal of the tube base 14 which would set up strains that might easily crack the tube if the tube holder were held in a fixed position.

In operation, when an electron tube base 14 or other device having a male portion or plug is inserted into the holder 10, the strips and their associated spring fingers first give slightly under the downward pressure exerted, but then furnish a practically rigid backing, in the axial direction, when the saddle 28 comes to rest in the channels 48 and 50 provided in the ring 46. Should there be any misalignment between any of the strips and the spring fingers, these elements will yield accordingly to permit adequate shifting of the same. Since each of the four spring fingers is thus enabled to move bodily to align itself with the respective complementary strip, each spring finger is able to contribute its share of the current flowing through the cathode of the tube.

While there has been described what is at present considered a preferred embodiment of the invention, it will be obvious to those skilled in the art that various changes and modifications may be made therein without departing from the invention, and it is therefore aimed in the appended claim to cover all such changes and modifications as fall within the true spirit and scope of the invention.

What is claimed is:

In a socket mounting for an electron tube, means for providing said socket with low cathode lead inductance comprising, in combination a metallic ring having opposite flat surfaces and provided with diametrically opposed
